Primary Examiner — Sanjeev Paul*Assistant Examiner* — Breana Copeland(74) *Attorney, Agent, or Firm* — Stetina Brunda Garred & Brucker**CLAIM**

The ornamental design for a sunglass, as shown and described.

DESCRIPTION

FIG. 1 is a front perspective view of the sunglass of the present invention showing our new design;

FIG. 2 is a front elevational view thereof;

FIG. 3 is a rear elevational view thereof;

FIG. 4 is a side view thereof;

FIG. 5 is a top plan view thereof; and,

FIG. 6 is a bottom plan view thereof.

The broken lines in the drawings are shown for the purpose of illustrating portions of the sunglass and form no part of the claimed design.
